(57) CLAIM

The ornamental design of a holder for a removable animal grooming comb, as shown and described.

DESCRIPTION

FIG. 1 is a perspective view of a holder for a removable animal grooming comb showing my new design;

FIG. 2 is a top view thereof;

FIG. 3 is a bottom view thereof;

FIG. 4 is an end view thereof, the opposite end view being a mirror image;

FIG. 5 is a side view thereof; and,

FIG. 6 is an opposite side view thereof.

The animal grooming comb shown in phantom in FIG. 1 is for illustrative purpose only and forms no part of the claimed design.
